UNITED STATES PATENT OFFICE

106,450

DESIGN FOR A PLAQUE

Douglas G. Matheson, Van Nuys, Calif.

Application July 12, 1937, Serial No. 70,363

Term of patent 3½ years

To all whom it may concern:

Be it known that I, Douglas G. Matheson, a citizen of the United States, residing at Van Nuys, county of Los Angeles, State of California, have invented a new, original, and ornamental Design for a Plaque, of which the following is a specification, reference being had to the accompanying drawing forming a part thereof.

I claim:

The ornamental design for a plaque, as shown.

DOUGLAS G. MATHESON.
